UNITED STATES PATENT OFFICE.

FRANK GATES FORTE, OF OAKLEIGH, NEAR MELEURNE, VICTORIA, AUSTRALIA.

ALARM-CLOCK.

1,171,511.

Specification of Letters Patent. Patented Feb. 15, 1916.

Application filed February 17, 1913. Serial No. 749,022.

To all whom it may concern:

Be it known that I, FRANK GATES FORTE, a citizen of the Commonwealth of Australia residing at "Glenmona," Warrigal Road, 5 Oakleigh, near Melbourne, in the State of Victoria and said Commonwealth, have invented new and useful Improvements in and Relating to Alarm-Clocks, of which the following is a specification.

10 This invention relates to devices for sounding alarm bells and the like and particularly to such devices of the kind in which at a single setting of the operating mechanism for a pre-determined time or 15 times any number of alarms may be given during the complete travel of the hour hand once around the dial of a clock. In devices of this kind as heretofore proposed, the alarm for any setting could only be sounded 20 for a predetermined interval.

The object of the present invention is to provide an improved alarm device of the above kind whereby alarms of varying duration can be given at will.

25 With this object in view the invention consists in providing means whereby any number of alarms may be set at a single operation in such manner that a short ring, a continuous ring, or a repeat ring may be given for each alarm. In the case of a continuous signal it would, of course, be necessary to rewind the alarm train before a further signal could be given.

30 The invention also consists in the novel features as hereinafter more particularly described and claimed.

A clock fitted with a reminder alarm constructed according to the present invention is particularly useful to commercial and 35 other business men as well as for domestic, theatrical, scholastic, or other purposes, where an alarm or signal is required at predetermined intervals and during a period of twelve hours which period comprises the 40 complete revolution of the hour hand arbor of an ordinary clock.

Furthermore, the device according to the present invention may be fitted to any clock of ordinary construction, or clocks may be 45 constructed specially to suit the alarm devices embodied in the present invention.

The accompanying drawings illustrate the present invention embodied in a clock of ordinary construction and in which:

Figure 1 is a view in front elevation of a 55 clock having the mechanical alarm devices peculiar to this invention embodied therein. Fig. 2 is a view in front elevation of the dial or face of the clock illustrating essential details. Fig. 3 is a view in vertical section of the mechanical devices embodied in this invention for controlling the alarms or signals. Fig. 4 is a view in side elevation of the device for controlling the setting of the alarm. Fig. 5 is a view in perspective 60 of a portion of the face glass of the clock illustrating a groove adapted to accommodate the device illustrated in Fig. 4. Fig. 6 is a view in side elevation of the face glass having the alarm and setting device fitted 65 thereto. Fig. 7 is a vertical central section of the device illustrated in Fig. 4. Fig. 8 is a view in perspective of an essential detail. Fig. 9 is an enlarged sectional view 70 illustrating the position and arrangement of 75 various essential features embodied in this invention. Fig. 10 is a side elevation of a portion of the device for controlling clock alarms or signals. Fig. 11 is a view in elevation of various mechanical parts illustrating a portion of the connecting means between the hands arbor and the trembler of the alarm or bell. Figs. 12, 13 and 14 are views in perspective of details embodied in Fig. 11. Fig. 15 is a view in perspective of 80 another portion of the said means illustrated in Fig. 10. Fig. 16 is a view of a portion of the rear elevation of the clock illustrating the position and arrangement of the regulating arm for the length or period 85 of ring or alarm. Fig. 17 is a view in elevation of a clock of ordinary construction having the devices embodied in this invention adapted to work in conjunction therewith, the cover and case of the clock being 90 removed. Fig. 18 is a view in sectional elevation of a portion of the devices embodied 95 in this invention, the alarm and time train of the gear wheels being indicated in their respective positions by dotted lines. Fig. 19 is a view in plan of a portion of Fig. 17. Figs. 20, 21, 22, 23, 24 and 25 are views in

perspective of essential and constructional details. Fig. 26 is also a view illustrating a constructional detail.

Like reference numerals indicate the same or corresponding parts in all the figures.

According to this invention the face of the clock is of special construction and consists of a ring 1 having two inwardly projecting flanges around the circumference thereof. 10 The inner flange 2 is the larger and is adapted to receive around the inside thereof a disk 3 of suitable material having the clock dial 4 attached thereto.

The inner and outer flanges 2, 5 are provided with a series of slots or holes 6 around the circumference thereof, of a number sufficient to indicate every five minutes of the hours indicated on the dial 4, thus in a twelve hour dial as illustrated, the ring 1 20 would be provided with one hundred and forty-four holes 6 as illustrated in Fig. 1 of the drawings. Alternatively, the holes 6 may be distanced at an interval of ten minutes relative to the dial as illustrated in Fig. 2 25 but it will be readily understood that the number of holes could be confined to any other periods of time and may be indicated as desired. A pin 7 is adapted to pass within each corresponding hole 6 in the flanges 2, 5 the 30 pin being provided with an enlarged head 7^a similar to an ordinary pin head positioned outside the flange 5. These pins 7 are frictionally held in their normal or inoperative position by ribs 8 formed around the periphery of the disk 3 which act in the manner of a flat spring, one rib being provided for each pin used.

The disk 3 and the dial 4 are centrally slotted to receive the end of the hands arbor 40 9 and the dial is indicated by the hours and minutes as ordinarily. Around the edge of the minute indicator is a second indicator 10 preferably printed in a different color and which indicates the five or ten minute or 45 longer intervals as required relatively to the period of time indicated on the face of the dial. A ring 11 held tightly in position is provided to inclose the ribs 8 and this ring is provided with a flange 12 to allow of a 50 better fit against the outer ring 1 carrying the pins 7 and to allow of the easy movement of the glass 14.

The arbor 9 carries the hands 13 as usual and the glass 14 is also positioned upon the 55 face of the clock, being loosely held by means of the flange 15 formed on the front edge of the cover or case 16. The glass 14 is adapted to be rotated being loosely mounted upon the ring 11 and held in position by the flange 15 above described. The glass is of 60 suitable thickness and is provided on its edge with a groove 17 having parallel faces adapted to receive a mechanism for regulating the position of the pins or pintles 7. 65 This regulating mechanism consists of a

case, the body 18 of which projects outwardly from the glass while its inner end 19 is squared to engage with the parallel faces of the groove 17 and fits flush therein. A pointer 20 projects within the glass along 70 the edge of the ring 11 and is bent downwardly at its end at approximately right angles to loosely engage the face of the dial 4 while at the same time, the end of the pointer is in line with the indicator 10 75 on the face of the dial 4. Lugs or ears 21 are formed on the outer end of the body 18 which rest against the glass face 14 to retain the device in position.

The outer end of the body 18 is formed 80 with a slot 23 to accommodate a small tube 24 the outer flange 25 of which is of greater diameter and projects beyond the body 18, being used as a grip for the fingers when adjusting or cutting out the device. This 85 tube 24 has a flattened projection 26 projecting through a rectangular or squared slot 27 formed in the inner end of the body, the end of the projection being formed with an upwardly projecting hook 28 adapted to 90 engage the head of any of the pins 7. Projecting centrally through the body and the tube 24 is a pin 29 passing through a slot 27^a in the inner end of the body 18 and adapted to engage or contact with the pins 95 7 arranged in and around the ring 1. A small pin 30 passes vertically through the pin 29 to limit the outward movement thereof and normally rests against the inner end 100 of the tube 24 within the body of the device, while a spring 31 passes around the pin 29 and the projection 26 and is adapted to return it and the pin 29 to their normal or inoperative positions. The projection 26 is formed on one side with a lug 26^a adapted 105 to engage one end of the spring 31, the other end of the spring being arranged to bear against the body 18. After the pin 7 has been returned to the normal or inoperative position by the projection 26 on the 110 tube 24 owing to the flange 25 being gripped and pulled outwardly against the spring 31 which is consequently brought into compression by the lug 26^a, the spring 31 is freed 115 and returns to the normal or extended position carrying the tube 24 and projection 26 to the normal position by acting against the lug 26^a on the projection 26.

When setting the alarm for various predetermined intervals during a period of 120 twelve or twenty-four hours the setting for the various times throughout the day is completed in one operation. This is effected by the device fitted to the glass face 14 of the clock, which device is moved around to the 125 points indicated at 10 corresponding to the time required and the desired pin 7 is then forced inwardly by the pin 29 thereby allowing the inner point to project past the flange 2 of the ring 1. 130

Should the device be set for one or several periods through the day and it is desired to reset the clock, the flanged tube 23 carrying the hook 28 is pulled outwardly 5 and thereby causes the particular projecting pin or pins 7 to be moved into the inoperative position.

Keyed upon the hour hand arbor immediately inside the disk 3, is a radial arm 32 extending to a point near the edge of the ring 1, the outer end 33 of the radial arm being bent at right angles to receive the spindle of a rotating roller 34 adapted to rotate in the direction of the hands arbor 15 along the path of the holes 6 through which the pins 7 are adapted to project when set for indicating an alarm. A pivoted catch consisting of a bent arm 35 is pivotally mounted at or near its center to a projection 20 36 of the radial arm 32, the outer end 37 of the pivoted catch 35 being bent to lie adjacent to the flange 2 of the ring 1, in order that the point 38 suitably tapered may engage with any of the pins 7 which are set to 25 project past the surface of the flange 2 of the ring 1. A flat or other spring 39 is carried by the radial arm 32 and is adapted to make contact with the catch 36 on its rearward movement, the spring not controlling the forward movement in any way. This spring makes contact with the catch 36 to the rear of the pivot on any backward movement of the radial arm 32, should the catch engage with a pin 7, and returns the 35 catch to the normal position. As the radial arm 32 rotates with the hour hand arbor and the catch 35 engages a particular projecting or operative pin 7 in order to permit an alarm to be given in the manner herein- 40 after described, the roller 34 is adapted to subsequently return the particular operative pin 7 to the normal position upon the continued rotation of the arm 32 and thereby leave this pin ready for resetting. The 45 end 40 of the bent arm 35 engages another bent arm 41 pivoted to a boss 42 on the radial arm 32 which in turn is adapted to engage by means of a lip 44 with a trip arm or lever 43 pivoted at 45 to a boss 46 on the 50 said radial arm 32, these arms 41 and 43 having a movement somewhat similar to a see-saw. The inner end of the trip arm is bent as at 47 in order to engage with the inner end of a pivoted controlling arm 48. The 55 inner end of this controlling arm 48 is formed with a hook or eye 49 passing around the hands arbor and around the collar of the wheel 50 outside the front plate 53. The controlling arm 48 is twisted in order 60 to enable it to be pivoted at 51 upon the pivot arm 52 fitted to the front plate 53. The upper end 54 of the controlling arm is pivotally connected to a sliding rod 55 projecting through the plates 53 and 56 65 and is arranged at approximately right an-

gles to the said controlling arm. At a suitable distance from the plate 56 a collar or button 57 is formed upon or fitted to the guide rod 55 while a second button is fitted to and near the outer end of said rod and 70 rests normally against the inside of the plate 56. This latter button 58 is cut away as illustrated in Fig. 15 to form a seat for a spring catch hereinafter referred to. The button 57 is provided at its upper edge with 75 a tapering lip 59 adapted to engage and hold a locking pin 60 fitted to the rocking spindle 61 carrying the trembler or hammer 62 of the bell 63. For the purposes of this invention, this locking pin 60 is not in its 80 ordinary position, being placed to the rear of the anchor 64 of the alarm escapement wheel 65, and being so placed, the devices embodied in this invention are enabled to 85 control the release or locking thereof.

A helical spring 66 is fitted around the guide rod and returns the whole of the parts to their normal positions immediately the pivoted catch 35 is released from contact 90 with one of the pins 7.

The combined movements necessary in the operation of the rod 55, arm 48, lever 43 and pivoted catch 35 tend to cause an outward movement to the hour hand arbor owing to the limited or slight outward 95 movement of the upper end 47 of the arm 43 which tends to force the hour hand arbor outwardly, but in order to limit any such movement of the hour hand arbor a washer 67 is fixed between the hands of the clock 100 on the minute hand spindle. The washer 67 only allows of a slight movement to the hour hand arbor and such movement being limited is not sufficient to be of any detriment to the effective operation of the mechanism. 105

The wheel 50^a working from the minute arbor and controlling the movement of the hour hand arbor according to this invention is positioned on the opposite side of 110 the arbor to that position in an ordinary clock, the pinion 50^b being also arranged to allow of freedom for the radial arm 32 in its movement around the flange 2 of the ring 1. 115

A spring catch 68 is adapted to seat upon the ledge formed by the cut away portion of the rear button 58 and projects from a fixed pin or rivet 68^a fitted to the rear plate. This spring catch 68 preferably projects upwardly at a slight angle and is formed at its free end with a lug 69 bent over parallel with the flat portion 70 of the rear button 58 toward and approximately in line with the lip 59 on the button 57. 125

That portion of the spring catch 68 formed with the lug 69 is approximately in line with the locking pin 60 on the rocking spindle 61 of the trembler 62 when the pin 60 is in the locked position. The free end 130

of the pin 60 is provided with a flat face 60^a as illustrated in Fig. 10, which is adapted to be engaged by the lug 69 of the spring catch for stopping the alarm train when giving a short signal in the manner hereinbefore described. Normally, that is to say, when the alarm is inoperative, the spring catch 68 does not engage this flat face 60^a of the pin 60.

10 The free end of the locking pin 60 is formed as illustrated in Fig. 10, being provided with a flat obliquely disposed face 71 which is adapted to be engaged by the tapered lip 59 of the button 57 when this button and the several other elements of the releasing mechanism are in their normal positions before an alarm is sounded and as illustrated in Figs. 3, 10 and 18 of the drawings. When the parts are in this position the alarm train is locked.

As the spring catch 68 is normally out of contact with the locking pin 60, then when the catch 35 engages one of the operative pins 7, the button 57 will be disengaged 25 from the locking pin 60 through the medium of the mechanism previously described and the alarm train consequently released to enable a short signal or alarm to be given by the subsequent stopping of the alarm train by the spring catch 68 which is now rendered operative by the means to be shortly described. It should be noted that a second and lower locking pin 89, illustrated in Fig. 18, the control and purpose 30 of which will be hereinafter described with reference to the continuous and repeat alarms, is rendered free to oscillate with the locking pin 60 at this time.

40 A locking arm 72 is pivoted intermediate the upper and lower ends to the rear plate 56 at the point 73 and is fitted with a distance washer. The purpose of this arm 72 is to control the operation of the spring catch 68 from the winding spindle of the 45 alarm train as hereinafter described. A spring 75 serves to urge the upper end of the locking arm 72, into engagement with the spring catch 68 and the lower end against a collar 74 of square or other configuration 50 which is rigidly mounted upon the winding spindle of the alarm train and is provided for the purpose of regulating the length of the short ring according to the shape and size of the collar.

55 The upper end of the arm 72 is bent rearwardly and bears lightly against the rear plate 56, while the lower end is bent inwardly and is adapted to engage the collar 74 at certain periods during the operation 60 of the device, at a point a short distance from the edge of the rear plate 56.

The end of the spring catch 68 is formed with a projecting lip 71^a which is bent slightly toward the locking pin 60, and is 65 adapted to be engaged by the upper end of

the locking arm 72 to urge the spring catch 68 against the pin 60 and thereby retain the latter in the locked position when giving a short signal.

The portion of the locking arm 72 that is 70 adapted to engage the lip 71^a is tapered to a knife edge, the face toward the rear plate 56 however being in the same plane as the remainder of the arm and is perfectly flat. Upon release of the alarm train as above described, the pivoted locking arm 72 is operated, this being effected and controlled by the collar 74 and during this operation, the arm 72 is caused to move across the face of the rear plate 56 out of engagement with 80 the spring catch 68. The precise operation and position of the parts to obtain a short alarm or signal will be hereinafter particularly described.

In order to obtain the continuous and repeat alarms the following means are employed in addition to those described above. The second or lower locking pin 89 referred to above is rigidly secured to the trembler 62. This locking pin 89 is adapted to be retained in the locked position by means of a pin 87 arranged to be engaged with the lower or free end of the locking pin 89 at certain periods to lock the alarm train as hereinafter described. The pin 87 is carried 95 by a plate 88 and projects therefrom toward the front of the clock, the plate 88 being slidably mounted upon the rear plate 56 and arranged obliquely thereto as illustrated in Figs. 17 and 18. The plate 88 and the 100 locking pin 89 are approximately in line with each other so as to allow the pin 87 to readily hold the lower locking pin 89 controlling the trembler when a repeat signal is being given. The plate 88 is constantly 105 urged in an upward direction under the action of a spring 100 secured at one end to the rear plate 56 and at the other end to a lug 101 provided upon the slidable plate 88. Slots 90 are provided at the upper and lower 110 ends of the plate 88 and through these slots pins 91 are passed. These pins are secured to the rear plate at the inner face thereof as illustrated in Fig. 18 and serve as the means upon which the plate 88 can slide at certain 115 periods to effect the release or locking of the alarm train. The enlarged heads of the pins 91 engaging the face of the plate 88 around the slots, retain the plate 88 in position relatively to the rear plate during the sliding 120 movement.

The pin 87 upon the slidable plate 88 is adapted to operate a bent lever 94 at certain periods during the operation of the alarm mechanism as hereinafter described. This 125 lever is pivoted at the bend 95 to the rear plate against which it bears closely while the lower end of one arm of the lever is formed with an eye 96 which is adapted to receive the pin 87, the internal dimensions of the 130

eye being greater than the diameter of the pin 87 so that there is a predetermined amount of play between these two members to permit the necessary relative movement between the pin 87 and the bent lever owing to the fact that the plate 88 and the pin 87 are restrained to move in a straight line, while the end of the lower arm of the bent lever 94 moves in the arc of a circle about the point at which it is pivoted.

The lower arm of the bent lever 94 is raised for a portion of the length at 95^a as illustrated in Fig. 21 to permit the plate 88 to be passed beneath it, while the upper arm is adapted to be passed between the rear plate and the button 58 at certain periods during the operation of the alarm mechanism to give a continuous or repeat signal as hereinafter described. A pin 92 is also mounted upon the slidable plate 88 and is adapted to engage the teeth of a wheel 93 on the arbor of one of the wheels of the time train mechanism for controlling the alarm train during the repeat signal as hereinafter described. The pin 92 does not lock the time train, but is merely held by the pressure of the spring 100 against the teeth of the wheel 93. The slidable plate 88 also carries a pin 98 which projects therefrom toward the rear of the clock and is adapted to be engaged by means to be shortly described for the purpose of adjusting the position of the slidable plate 88. The pin 98 is arranged to slide in a slot 99 formed in the rear plate 56.

In order to regulate and control the length of the alarm or signal a regulator 79 is provided which is disposed upon the outer face of the rear plate 56 and pivoted at the point 81. The regulator comprises a cam 80 arranged at the lower end and an arm 79 which is bent and is adapted to project outwardly through a slot 82 formed in the removable cover of the clock casing for manipulation by the operator.

The cam 80 is provided with two working surfaces 84 and 85 respectively, the surface 84 being adapted to engage a pin 86 on the locking arm 72 according to the position of the regulator, and consequently remove the locking arm 72 from engagement with the spring catch 68 and from the collar upon the winding spindle of the alarm train 76, 78 for a purpose to be hereinafter set forth. The pin 98 is adapted to be engaged by both cam surfaces 84 and 85 according to the position of the regulator for the purpose of controlling the position of the pin 87 carried by the slidable plate 88 and also controlling the position and movements of the bent arm 94 as well as effecting engagement or disengagement of the pin 92 with or from the toothed wheel 93.

The regulator 79 is adapted to be moved by the operator into one of three positions

designated "a", "b", and "c" in order to control the mechanism to obtain a short signal or alarm, a continuous signal and a repeat signal respectively. When the regulator is moved into the position designated "a" the mechanism is so controlled by the cam 80 that a short signal can be given. The cam surface 84 then engages the pin 98 upon the slidable plate 88 and moves the latter in a downward direction determined by the guide pins 91 and in a line extending from the top to the bottom of the plate 88. The extent of this downward movement is such that the pin 92 is disengaged from the wheel 93 of the clockwork train and the pin 87 disengaged from the lower locking pin 89 of the trembler 62. As the movements of the bent lever 94 are controlled by the movements of the slidable plate 88, the upper arm of the bent lever 94 will now be retained below the button 58. At the same time the upper end of the locking arm 72 is urged into contact with the spring catch 68 under the action of the spring 75 as the cam surface 84 of the regulator cam 80 is not in engagement with the pin 86 upon the locking arm 72 as will be clearly understood from Fig. 17 of the drawings, the lower end of the arm 72 simultaneously engaging the collar 74 upon the winding spindle of the alarm train as hereinbefore described. Further, it should be noted that the locking pin 60 is locked by the lug 59 of the button 57 this alone preventing operation of the alarm train.

The several parts of the mechanism being in the positions described above for the short signal position, the operation of the device from the dial of the clock for giving the short signal or alarm will now be described.

When the pivoted catch 35 engages one of the projecting pins 7 set to give the desired short signal or alarm at a predetermined time, the intermediate levers, hereinbefore described, which are connected to the catch 35 are actuated and this causes the pivoted arm 48 to be moved into an approximately vertical position as illustrated in chain lines in Fig. 10. Simultaneously with this movement of the arm 48 the rod 55 carrying the buttons 57 and 58 is moved in a direction longitudinally of the rod 55 to the right (see Fig. 10) for a short distance and consequently effects the disengagement of the button 57 from the locking arm 60. Immediately this occurs the trembler 62 and consequently the alarm train is released and the alarm sounded. The collar 74 immediately commences to rotate and continue to rotate slowly during the time that the alarm train is released to give the short signal or alarm.

Assuming the controlling collar 74 to be of square configuration as illustrated, then during rotation, one of the corners engages

the lower end of the pivoted locking arm 72 and forces the upper end thereof out of engagement with the spring catch 68. Upon the continued rotation of the collar 74, as 5 the corner thereof passes the lower end of the arm 72, the latter moves over one of the flat faces of the collar while the upper end of the arm 72 is swung back again into engagement with the spring catch 68 under 10 the action of the spring 75.

For a collar of square configuration the arm 72 would be caused to engage the spring catch 68 every quarter of a revolution of the collar and consequently also of the winding 15 spindle of the alarm train. The time occupied during one revolution of the toothed wheel 76 is approximately ninety seconds and the period of ring is limited by the number of sides on the collar 74, for instance, a 20 five sided collar would give a ring lasting eighteen seconds, while a four sided collar as illustrated would give a ring lasting 22 $\frac{1}{2}$ seconds. It is, of course, to be understood 25 that the collars are interchangeable. It should be observed that when the arm 72 is thus moved to engage the spring catch 68, the button 58 being now in a position a 30 short distance from the rear plate 56, the arm 72 passes between the rear plate and the button 58 and thrusts against the lip 71^a of the spring catch thereupon forcing the latter into engagement with the flat face 60^a of the locking pin 60, the position of the button 58 upon displacement to the right (see 35 Fig. 10) permitting this action to be effected. The locking pin 60 and consequently the alarm train is thus locked again, thereby causing the bell to cease ringing until the pivoted catch 35 engages another operative 40 pin 7.

As soon as the catch 35 has passed the particular projecting pin giving the desired short alarm, the button 57 and rod 55 together with the other coöperating levers 45 hereinbefore described are returned by the spring 66 to their normal position in which the button 57 is again in engagement with the locking pin 60 thereby locking the trembler and alarm train, while the spring catch 50 68 is moved out of engagement with the flat face 60^a of the locking pin 60 by the button 58 upon movement to the left (see Fig. 10) simultaneously with the movement of the button 57, and the spring catch is forced 55 against the rear plate 56. During this operation the arm 72 is swung slightly away from the spring catch 68 by the pressure exerted upon the spring catch when the button thrusts it toward the rear plate and is 60 returned by the spring 75 into engagement with and at the front of the spring catch, thereby permitting the lug 59 of the button 57 to hold the locking pin 60 until released again by the catch 35 engaging another 65 operative pin 7.

When the regulator is moved by the operator into the position designated "b" for a continuous alarm or signal, the upper end of the locking arm 72 is forced out of the normal position in engagement with the 70 spring catch 68 and the lower end out of engagement with the collar 74, as hereinbefore described, by the cam surface 84 of the regulator which surface now engages the pin 86 upon the arm 72 (see Fig. 17). Simultaneously with this movement of the regulator the slidable plate 88 is urged upwardly 75 toward the cam surface 85 under the action of the spring 100. The cam surface 85 is so shaped that the pin 87 is now moved upwardly with the plate 88 to such an extent that the pin 87 still does not engage the free end of the locking arm 89. The lower arm of the bent lever 94 is also moved upwardly and causes the upper arm to be moved into 80 contact with the button 58 which it will be observed is in close contact with the rear plate. The pin 92 is also out of engagement with the toothed wheel 93. When the parts are in this position the pin 98 on the slid- 85 able plate 88 is not in engagement with the cam surface 85 of the regulator. A continuous alarm or signal can now be given through the medium of one of the projecting pins 7 engaging with the catch 35, the 90 release of the alarm train being effected in the same manner as for the short alarm or signal. In order that this operation may be effected it is pointed out that the locking pin 60 is locked normally that is to say, before the alarm is given, by the lip 59 of the button 57, the parts coöperating with this locking pin taking up positions exactly the 95 same as the normal positions for the short alarm or signal. As the locking arm 89 is 100 now free, then immediately the locking arm 60 is released the alarm is sounded. For a continuous ring the alarm is sounded until the spring runs down. In order therefore to prevent the alarm being stopped when the 105 catch 35 passes the particular projecting pin 7 with which it is in engagement, the bent arm 94 automatically becomes operative the instant the alarm train is released.

Immediately the rod 55 and buttons 57 110 and 58 are moved to the right (see Fig. 10) the button 58 is moved a short distance from the face of the rear plate 56 as previously described. This enables the upper arm of the bent lever 94 to move farther upwardly 115 to a position between the rear plate and the button and so prevent the return of the button 58 and consequently of the rod 55 and the locking button 57 when the catch 35 passes the particular operative pin 7 with 120 which it is in engagement, thereby maintaining the locking pin 60 free to oscillate with the trembler. This movement of the bent lever 94 is adapted to be effected owing to 125 a further slight upward movement of the 130

slidable plate 88 which can take place under the action of the spring 100 until the pin 98 upon the plate 88 engages the cam surface 85 of the regulator. It should be observed that this further movement imparted to the plate 88 is such that the pin 87 still does not engage the lower free end of the locking pin 89. The alarm is therefore permitted to be sounded until the spring runs down completely notwithstanding that the catch 35 has passed one of the operating pins 7. If a further continuous alarm is to be sounded by a further projecting pin 7 already adjusted for engagement with the catch 35, then, of course, the alarm train would have to be rewound before this can take place. It will, of course, be necessary to remove the upper end of the bent arm from the position between the rear plate and the button 58 in order that the several parts of the mechanism may be returned to their normal positions ready for a further alarm to be given. This may be effected by moving the regulator into the position designated "a," so that the pin 87 is then moved in a downward direction with the plate 88 as hereinbefore described and simultaneously draws the upper end of the bent lever 94 to a position below the button 58, thereby enabling the buttons 57 and 58 and coöperating members to be returned to their normal position by the spring 66.

When the regulator is moved by the operator into the position designated "c" for a repeat signal or alarm, the locking arm 72 is still disengaged from the spring catch 68 and the collar 74 upon the winding spindle of the alarm train by engagement of the cam surface 84 of the regulator with the pin 86 of the locking arm 72. In this case also the locking pin 60 and coöperating parts are normally in the same positions as for the short signal or the continuous signal and is adapted to be released in precisely the same manner as in these cases. The slidable plate 88 still remains in the position occupied by it during the inoperative stage for giving the continuous alarm or ring and the pin 87 is out of engagement with the lower end of the locking arm 89. The parts being in this position, the repeat alarm can now be given when the locking pin 60 is released through the medium of the catch 35 and one of the projecting pins 7 in the same manner as in the case of the short and continuous signals. Immediately the button 58 moves to the right (see Fig. 10) upon this operation the upper arm of the bent lever 94 moves upwardly between the rear plate and the button 58, but owing to the position of the regulator, it moves a greater distance than for the continuous ring position. The extent of this movement is controlled by the slidable plate 88 which also moves upwardly to such an extent that the pin 87 now engages

the free end of the locking arm 89, the pin 98 preferably engaging the cam portion of the regulator. Simultaneously with this movement the pin 92 engages the teeth of the wheel 93 (see Figs. 17 and 18) provided on one of the arbors of the time train, and together act as an escapement device as and for the purpose hereinafter described. As the wheel 93 rotates with the time train by reason of the pin 92 engaging one of the teeth thereof and the plate 88 carrying this pin being restrained to move in a predetermined path by the guide pins 91, the plate 88 is drawn downwardly independently of the cam of the regulator to such an extent that the locking pin 87 becomes disengaged from the locking pin 89, the pin 98 it should be noticed being free to move toward the lower end of the slot 99. The alarm is thereby permitted to be given, the locking pin 60 being maintained disengaged from the button 57 irrespective of the engagement of the catch 35 with one of the projecting pins 7 by the bent lever 94 as hereinbefore described with reference to the sounding of a continuous alarm. As soon as the particular tooth of the wheel 93 passes the pin 92, the plate 88 is urged upwardly under the action of the spring 100, so that the pin 87 again engages the lower end of the locking arm 89 and again locks the alarm train until another tooth of the wheel 93 engaging the pin 92 again draws the plate 88 downwardly. In this manner it will be observed a series of intermittent or repeat rings can be given until the spring runs down.

The withdrawal of the bent arm 94 from the position between the rear plate and the button 58 may be effected in a similar manner as in connection with the sounding of the continuous alarm.

The wheel train and mechanism of the alarm train referred to above consists of the winding spindle and gear wheel 76 carrying the usual spring 77, (see Fig. 17) and also the usual intermediate train of gear wheels 78 for actuating the alarm escapement wheel 65, which in turn actuates the trembler 62 by means of the U-shaped anchor 64 on the rocking spindle 61 upon release of the locking pin 60.

The supports 102 for the clock (see Fig. 1) are attached to the case 16 in any desired manner but preferably by soldering. They may, however, be secured to a strengthening ring 103 (see Fig. 3) fitted inside the case 16 in any suitable manner. Bearers 104 which project from the edge of the ring 1 are provided and connect with angle arms or supports 105 (see Fig. 17) carrying the plates 53 and 56 supporting the clock mechanism. The whole of these parts are clamped in position by screws 106 (see Fig. 3).

It is to be understood that the mechanical

alarm device according to this invention can be applied to all forms of clocks and the details of construction can be modified as desired without departing from the principle underlying the invention.

What I claim and desire to secure by Letters Patent of the United States is:—

1. The combination with a clock work mechanism and an alarm device, of means whereby any number of alarms at intervals such as five minutes may be set at the one time, each giving at a predetermined time during the period of time indicated upon the dial of the clock, a short alarm, a continuous alarm, or a repeat alarm.
2. The combination with a clock work mechanism and an alarm device, of a device having means for setting a plurality of alarms at will at one time for predetermined times during the period of time indicated on the dial of the clock mechanism and also having means for re-setting or cutting out the alarms at will, automatic means for returning the signal starting means to normal after each alarm signal has been given, and means for causing to be given at each of the said predetermined times, a short alarm, a repeat alarm or a continuous alarm.
3. The combination with a clockwork mechanism and an alarm device, of means whereby any number of alarms may be set each to give, at a predetermined time during the period of time indicated upon the dial of the clock, a short alarm, a continuous alarm or a repeat alarm.
4. The combination with a clockwork mechanism and an alarm device, of a device having means for setting a plurality of alarms at will at one time for predetermined times during the period of time indicated on the dial of the clock mechanism and also having means for resetting or cutting out the alarms at will, and means for causing to be given at each of the said predetermined times, a short alarm, a continuous alarm, or a repeat alarm.
5. The combination with a clockwork mechanism and an alarm device, of a device having means for setting a plurality of alarms at will at one time for predetermined times during the period of time indicated on the dial of the clock mechanism and also having means for resetting or cutting out the alarms at will, and a regulator for controlling the duration of the alarm and for causing to be given at each of the said predetermined times, a short alarm, a continuous alarm or a repeat alarm.
6. The combination with a clockwork mechanism an alarm device and a casing for the clockwork and alarm mechanisms, of means for setting a plurality of alarms at one time for predetermined times during the period indicated on the dial of the clock,
- comprising a ring fitted to the front of the 65 clockwork casing, two inwardly projecting flanges upon the ring, having a series of holes or slots around the circumference thereof, pins adapted to be received in said holes or slots, a disk mounted on the outside 70 of the inner flange, means provided at the edge of the disk for engagement with the said pins, a clock dial carried by the disk, an indication upon said dial, a flange upon the clock casing, a device for controlling the 75 setting of the pins rotatable within said flange, means upon the controlling device for adjusting the position of the pins in the holes or slots of the flanged ring, and means for causing to be given at each of the said 80 predetermined times, a short alarm, a continuous alarm or a repeat alarm.
7. The combination with a clock work mechanism an alarm device and a casing for the clockwork and alarm mechanisms, of a 85 glass face having a groove formed at the periphery, a clock dial, a plurality of sliding pins arranged in holes or slots around the dial, a contrivance fitted within the groove formed in the glass face, means carried by 90 said contrivance for engaging the sliding pins in order to set the sliding pins for a predetermined time or times indicated upon the dial or reset said pins, a radial arm mounted for rotation upon the clock dial, 95 means upon the radial arm for effecting release of the alarm train to cause the sounding of the alarm, and means for causing to be given upon the release of the alarm train, a short alarm, a continuous alarm or a re- 100 peat alarm.
8. The combination with a clockwork mechanism an alarm device and a casing for the clockwork and alarm mechanisms, of a glass face having a groove formed at the periphery, a clock dial, a plurality of sliding pins arranged in holes or slots around the dial, a contrivance held within the groove 105 formed in the glass face and comprising a casing a pointer carried by the casing a pin 110 slidably mounted within the casing and adapted to engage and set the slidable pins disposed around the dial of the clock and a spring controlled slidable hook member disposed partly within and partly projecting 115 from the casing and adapted to reset or cut out at will the operative slidable pins disposed around the clock dial, a radial arm mounted for rotation upon the clock dial, means upon the radial arm for effecting release of the alarm train to cause the sounding 120 of the alarm, and means for causing to be given upon the release of the alarm train, a short alarm, a continuous alarm or a repeat alarm.
9. The combination with a clockwork mechanism a casing for the clockwork, of a glass face having a groove formed at the pe- 125

- riphery, a clock dial having holes or slots around it, a plurality of sliding pins arranged in the holes or slots, a contrivance fitted within the groove formed in the glass 5 face, means carried by said contrivance for engaging the sliding pins in order to set the sliding pins for a predetermined time or times indicated upon the dial or reset said pins, a radial arm mounted upon the hour 10 hand arbor of the clock, a pivoted catch carried by said radial arm and adapted to engage any of the operative pins set to project into the path of movement of the said catch, a rocking spindle, an alarm escape- 15 ment device, and a trembler or hammer carried by the spindle, an alarm bell, a controlling pin on said rocking spindle, intermediate trip or other mechanism between the catch and the controlling pin, means for 20 causing to be given at each of the predetermined times, a short alarm, a continuous alarm or a repeat alarm, and a roller upon the said radial arm for returning the sliding pins disposed around the dial of the clock to 25 their normal or inoperative position and adapted to be moved along the path of the holes or slots through which the operative pins are adapted to project, substantially as set forth.
- 30 10. In an alarm clock, a winding spindle, means for controlling the length of the alarm comprising a squared or other multisided collar rigidly mounted upon the winding spindle, a pivoted locking lever in frictional 35 contact with said collar, an escapement wheel, a rocking spindle, an anchor on the latter spindle engaging the escapement wheel, a locking pin rigidly attached to said rocking spindle, and a spring catch adapted to 40 engage said locking pin, all substantially as set forth.
11. In an alarm clock an hour hand arbor, a radial arm carried thereby, a pivoted catch upon the radial arm, a dial, slid able 45 pins disposed around the dial and adapted to be engaged by said pivoted catch, an alarm escapement wheel, a winding spindle, means for regulating the length of the alarm comprising a square collar rigidly mounted 50 upon the winding spindle, a pivoted locking lever the lower end of which is adapted to frictionally engage the square collar, a rocking spindle, a hammer carried by the spindle, a locking pin rigidly attached to said 55 rocking spindle, and a spring catch adapted to be engaged by the upper end of the said locking lever and hold the said locking pin when the alarm has been given and until the 60 release of the said pivoted catch, substantially as set forth.
12. In an alarm clock comprising clock-work mechanism an alarm device and a casing for the clockwork and alarm mechanisms, a regulator adapted to control the length of 65 the alarm comprising a pivoted cam, two or more working faces upon said cam and a regulating arm projecting through a slot formed in the rear of the clock casing, a spring catch, an alarm train, a winding spindle, a square or other collar rigidly mounted 70 upon the winding spindle of the alarm train, a pivoted locking arm adapted to engage both the spring catch and the said collar, a pin or projection upon said locking arm adapted to be engaged by one of the said 75 cam faces in order to move the locking arm out of engagement with the spring catch and also away from the said collar, thereby permitting the mechanism to be set to give a repeat or continuous alarm, substantially as 80 set forth.
13. In an alarm clock comprising clock-work mechanism, front and rear plates carrying said clockwork an alarm device and a casing for the clockwork and alarm mechanisms, a regulator adapted to control the length of the alarm comprising a pivoted cam, two or more working faces provided on 85 said cam, a spring controlled guide plate adapted to slide upon the rear plate of the clockwork mechanism, projecting pins upon said guide plate, a toothed wheel upon one of the arbors of the time train and adapted to be engaged by one of the said pins, a rocking spindle carrying the hammer, a locking pin rigidly attached to said rocking spindle, mechanism for controlling said locking pin, a second locking pin rigidly secured to said rocking spindle, a pivoted bent lever adapted to engage the second pin on the said 90 guide plate and cut out the mechanism controlling said locking pin allowing the second pin on the guide plate to control the movement of the second locking pin during a repeat alarm immediately the mechanism has 95 been operated and released, substantially as set forth.
14. In an alarm clock comprising clock-work mechanism, front and rear plates carrying said clockwork an alarm device and a casing for the clockwork and alarm mechanisms, a regulator adapted to control the alarm and cause a short alarm, a continuous alarm or a repeat alarm to be given comprising a pivoted cam, a spring controlled 100 guide plate adapted to slide upon the rear plate of the clockwork mechanism, projecting pins upon said guide plate, one of said pins being arranged to move in a slot provided in the rear plate supporting the clock-work and adapted to be engaged by the cam at various points during its travel, a pivoted locking arm, a pin upon said locking arm also adapted to be engaged by the cam 105 at various points during its travel, a rocking spindle carrying the hammer, a locking pin rigidly attached to said rocking spindle, a second pin on the guide plate adapted to 110
- 120
- 125

engage said locking pin, a bent arm carried by the rear plate and formed with a slot inclosing the said second pin on the guide plate, a toothed wheel upon one of the arbors of the time train, a third pin upon said guide plate being adapted to engage said toothed wheel, and mechanism for starting in all instances the release of the alarm train

from the dial of the clock, substantially as set forth.

In testimony whereof I have affixed my signature in the presence of two witnesses.

FRANK GATES FORTE.
